UNITED STATES PATENT OFFICE.

HUGH ALEXANDER THOMSON, OF SHAWLANDS, SCOTLAND.

SWITCH MECHANISM.

No. 823,647.

Specification of Letters Patent.

Patented June 19, 1906.

Application filed September 21, 1905. Serial No. 279,454.

To all whom it may concern:

Be it known that I, HUGH ALEXANDER THOMSON, a subject of the King of the United Kingdom of Great Britain and Ireland, residing at Shawlands, Renfrewshire, Scotland, have invented certain new and useful Switch Mechanism, of which the following is a specification.

My invention relates to improvements in switch mechanism for operating railway-points; and the objects of my improvement are, first, to obtain a smoothness and simplicity of working combined with safety in operating; second, to reverse and hold the switch-blades securely in either set position; third, to prevent derailment usually caused by partly-shut blades; fourth, to obtain automatic shifting and setting of the points by the passing through trailing ways of a train or vehicle, and, fifth, to provide automatic lubrication of the working parts. I attain these objects by the mechanism illustrated in the accompanying drawings, in which—

Figure 1 is a cross-sectional elevation, and Fig. 2 is the corresponding sectional plan. Fig. 3 is a sectional elevation showing a slight modification. Figs. 4 and 5 are respectively cross-sectional and longitudinal elevations. Fig. 6 is a cross-sectional elevation; Fig. 7, a longitudinal sectional elevation with toggle-arm removed, illustrating a modified construction of the mechanism. Figs. 8 and 9 are end and side views of an alternative arrangement of spring and which I may substitute for the springs shown by Figs. 6 and 7.

Similar characters refer to similar parts throughout the several views.

The switch mechanism is fixed outside the track on sleepers 1, suitable holes being provided for screw-bolts, and it is so set that the lever-handle works parallel with the rail.

As shown by Figs. 1, 2, and 3, I construct a case 2, preferably of cast-iron. Inside this box I mount, to turn on spindles 3 and 4, two segmental toothed bevel-wheels 5 and 6, which gear with each other. To the wheel 5 a lever-handle 7 is fixed. On the rim of wheel 5 two toggle-arms 8 and 9 of T shape are securely recessed and fulcrumed. The cross-piece of each of these toggle-arms is of D form to enable it to pass through two eyes cored on the wheel-rim and to retain its fulcrumed position within the circular cavity 12. The other ends of the arms are fitted to slide in collars 13 and 14, pivoted in the cas-

ing. Round each arm 8 and 9 I mount a spiral compression-spring 10 11. The bevel-wheel 6 forms part of a bell-crank lever 15, to one end of which it is cast, the other end being attached to the pull-rod of the points. For the purpose of lubricating the spindle 3 and teeth of wheels 5 and 6 an aperture 16 is provided in the cover of the casing to communicate with a slot 17, which extends downward to the spindle 3 and from thence by a hole 18, Fig. 3, to the wheel-teeth.

The modified arrangement shown by Fig. 3 differs from Figs. 1 and 2 in having the toggle-arm 8' fulcrumed on the wheel 6. The other end of the arm is fitted to slide in a collar 13'. Round this toggle-arm I mount a spring 10'.

The action of the mechanism is as follows: On operating the lever-handle 7 circular motion is transmitted to the wheels 5 and 6 and from thence to the pull-rod of the points. Also when the switch-blades are run through trailing ways by the flanged wheel of a railway-vehicle and changed to another set position the motion given to the switch-blades and conveyed through the point-rod to the lever 15 reverses the switch mechanism, and the springs retain the points in their changed position.

By another arrangement, Figs. 4 and 5, I construct a metal case 2. Through the center of the case is fixed a metal axis 3, and on this axis a spiral cam or worm 4 is centered to turn. The worm consists in this arrangement of a metal cylinder, on the circumference of which a groove is formed. The center of the cylinder is cored out and fulfills the function of an oil-well for lubricating purposes. Inside the casing 2 and engaging with the worm a toggle or knuckle joint is fitted. The joint is composed of a sliding piece 5, set-pin, (shown dotted,) and two toggle-arms 6 and 7. The sliding head 5 has sloping sides and is adapted to slide in a similarly-shaped groove formed in the casing. It is provided with a chamber to receive the circular-headed ends of the two toggle-arms, the other ends of the arms being free to slide in collars 15 and 16, pivoted in the casing. To each arm a shoulder-piece 21 22 is cast, the under side being tapped to receive the screws 12 13. Around each arm a spring 10 11 is mounted, and from arm to arm on screws 12 13 a tension-spring 14 is stretched. To diminish friction a conical roller 8 on set-pin is provided. The sliding head 5 forms

part of the pull and push bar 17, to one end of which it is cast or screwed, the other end being attached to the pull-rod of the points. A lever-handle 9 is secured to one end of the 5 worm. To assure lubrication, already referred to, I introduce by the aperture 19, Fig. 5, a quantity of oil into the worm-core 20, Fig. 4. From the core to the groove a hole 18 is drilled, and its position is vertically 10 above the conical roller 8 at mid-travel and during the movement of the sliding head 5. Thus oil is automatically supplied by the movement of the worm to the spindle 3, roller 8, and set-pin, and from thence to the 15 sliding head and groove. The action of this worm combination is as follows: On operating the hand-lever 9 a circular motion is given to the worm 4, which transmits a reciprocating motion to the bar 17. Also when 20 the switch-points are run through trailing ways by the flanged wheel of a vehicle and changed to another set position the motion thus given to the switch-blades and conveyed through the point-rod to the pull and 25 push bar 17 reverses the switch mechanism and the springs retain the points in their reversed position.

As an alternative arrangement I combine in a modified form the mechanism illustrated 30 by Figs. 1, 2, 4, and 5. I construct a metal casing 2, Figs. 6 and 7, and in it I center to turn on a spindle 3 a spiral cam 4 of spherical shape and having the top and bottom half grooved left hand and right hand, respectively. Similarly, as in Figs. 1 and 2, I fulcrum two compression-springs 5 and 6 on the cylindrical portion 7. In addition to these 35 two springs I stretch on screws 10 11 the tension-spring 9. The spiral cam 4 engages with the pull and push lever 12, which is pivoted to move in the casing on trunnions 13. At the lower end of the pull and push lever a hole is drilled for attachment to the rod of the points. To insure perfect lubrication of the spiral block 14, I introduce oil 40 at O, Fig. 7, to the core similarly as in Figs. 1, 2, and 3 and convey it to the block by a hole drilled through the spherical shell to the core. To the end of the spiral cam a lever 8 45 is secured. I may substitute for the tension-spring 9 the spring 5', Figs. 8 and 9, and where a knife-edge projection 2' is added to increase the compression of the spring 5'. On the arm 15 I insert to slide the cross- 50 head 16, which bears on the sloping surface of the projection 2'. The arm 15 is fulcrumed on the projecting portion 7, the other end of the arm being free to slide in a collar 17, pivoted in the casing 2. 55 The action of the mechanism is as follows: On operating the lever-handle 8 a circular motion is given to the spiral cam 4 and the pull and push lever 12 and which is transmitted to shift the points. Also when the 60 points are run through trailing ways by the

flanged wheel of a train or vehicle and changed to another set position the motion thus given to the switch-blades and conveyed through the point-rod to the pull and push lever 12 reverses the switch mechanism, and the springs retain the points in their reversed position. 70

From the descriptions given of switch mechanism, and as illustrated by Figs 1 to 9, it is evident that during the shifting of the 75 switch-blades from one set position to the other either by means of the lever-handle or by a flanged wheel of a train or vehicle passing trailing ways through the points the springs for the first half of the travel offer a 80 resistance to motion until the mid-travel of the switch-blade, the point of equilibrium or dead-center of the mechanism is reached, and when passed the stored energy in the springs is utilized to assist in reversing or shifting the 85 points. In the switch mechanism, as shown, the compression and tension springs constrained to act as thus described I distinguish by the term "reversible." I here add that in the switch mechanism, as shown at 90 Figs. 4 and 5, I may not only use reversible springs, but may by a slight alteration in the shape of the casing and position of the pivoted collars substitute longer springs. In this modified arrangement the cross-section, 95 Fig. 4, applies, and the letter h, Fig. 5, shows the altered position of the two recesses which are formed opposite each other to receive the two pivoted collars 15 and 16. Then if the points are run through trailing ways by the 100 flanged wheels of a train or vehicle and forced open or operated by the lever-handle the switch-blades return to their original position when the train has passed through them or when the lever-handle has been released. It is shown that tension-springs can 105 be combined with compression-springs, Figs. 4, 5, 6, and 7. I may combine tension and compression springs, or I may substitute the one for the other. 110

I am aware that springs have before been employed in switch mechanism, but of an entirely different type and procuring a different result and that two British patents of date December 1, 1900, and April 14, 1903, 115 have been granted me embodying my methods of worm and toothed wheel-gearing; but I am not aware that the springs and gearing have ever been used in combination.

Having now described my invention, what I claim, and desire to secure by Letters Patent of the United States, is—

1. An apparatus of the class described comprising in combination a member adapted to be thrown in opposite or set positions, a 125 switch-throwing element in operative relation with said member, and yieldingly-acting means engaging said member on opposite sides of its axis and serving to hold it in opposite or set positions, said means exerting 130

- pressure on said member to force the same toward said element.
2. An apparatus of the class described comprising in combination a member having a horizontal axis of movement and adapted to be swung in a vertical plane in opposite or set positions, a switch-throwing element in operative relation with said member, and springs engaging said member above and below its axis, the outer ends of said springs being mounted above the axis of said member.
3. An apparatus of the class described comprising a switch-throwing member adapted to be thrown in extreme or set positions to open and close the switch-points, springs engaging said member at their inner ends on opposite sides of its axis to maintain said member in set positions, fulcrumed mountings for the outer ends of said springs, said fulcrumed mountings being located above the axis of said member.
4. An apparatus of the class described comprising a switch-throwing member adapted to be thrown in opposite extreme or set positions to open and close the switch-points, springs engaging said member on opposite sides of its axis to maintain said member in set positions, said springs being mounted at their outer ends at points above the axis of said member, and a lever connected with said switch-points and geared to said member.
5. An apparatus of the class described comprising a switch-throwing member provided with gear-teeth and adapted to be thrown in extreme or set positions to open and close said switch, springs engaging said member on opposite sides of its axis to maintain said member in set positions, said springs being mounted at their outer ends at points above the axis of said member, and a bell-crank lever connected with said switch and provided with gear-teeth adapted to mesh with the teeth of said member.
6. An apparatus of the class described comprising a switch-throwing member provided with gear-teeth and adapted to be thrown in extreme or set positions to open and close said switch, springs engaging said member at their inner ends on opposite sides of its axis to maintain said member in set positions, fulcrumed mountings for the outer ends of said springs, said mountings being movably secured at points above the axis of said member and a bell-crank lever connected with the switch-points and provided with gear-teeth adapted to mesh with the teeth of said member.
7. An apparatus of the class described comprising a switch-throwing member provided with gear-teeth and adapted to be thrown in extreme or set positions to open and close said switch, springs engaging said member at their inner ends on opposite sides of its axis to maintain said member in set positions, fulcrumed mountings for the outer ends of said springs, the said fulcrumed mountings being located above the axis of said member, and a bell-crank lever connected with the switch-points and provided with gear-teeth adapted to mesh with the teeth of said member.
8. An apparatus of the class described comprising a switch-throwing member provided with gear-teeth and adapted to be thrown in extreme or set positions to open and close said switch, said member having an oil-conduit extending from its upper portion and delivering to said gear-teeth, springs engaging said member at their inner ends on opposite sides of its axis to maintain said member in set positions, fulcrumed mountings for the outer ends of said springs, the said fulcrumed mountings being located above the axis of said member, a bell-crank lever connected with the switch-points and provided with gear-teeth adapted to mesh with the teeth of said member, and a casing for said apparatus provided with an oil-hole registering with the receiving end of said oil-conduit.
9. An apparatus of the class described comprising in combination a member adapted to be thrown in opposite set positions, a switch-throwing element in operative relation with said member, springs engaging said member on opposite sides thereof and in planes oppositely disposed with respect to the axis of said member, both of the outer ends of said springs being anchored in a plane at one side of the points of engagement of said springs with said member and at one side of the axis of said member.

In testimony whereof I have signed my name to this specification in the presence of two subscribing witnesses.

HUGH ALEXANDER THOMSON.
